FIG. 1

FIG. 2

INVENTOR

Charles H. Croney

By Ruchey & Watts

ATTORNEYS

UNITED STATES PATENT OFFICE

CHARLES H. CRONEY, OF BRUNSWICK, GEORGIA

MARSH ANCHOR

Application filed October 29, 1928. Serial No. 315,891.

This invention relates to anchors and is particularly adapted for use with dredges and the like, where the anchor must frequently be situated in shallow water or ashore, and 5 where it is desired to effect a secure anchorage and insure the anchor remaining in a definite position.

It is an object of the present invention to provide an anchor which is simple in construction and which can be readily and definitely located and caused to imbed itself in the earth.

Another object is to provide an anchor which will provide a very secure anchorage 15 when placed in operative position.

Other objects will hereinafter appear.

The invention will be better understood from the description of one practical embodiment thereof illustrated in the accompanying drawings, in which:

Fig. 1 is a front elevation of the anchor;

Fig. 2 is a plan view of the anchor in the position it assumes when engaging the earth, and

Fig. 3 is a section thereof taken on line 3—3 of Fig. 2.

The anchor consists of a substantially rectangular flat plate 1, the lower two corners of which are rounded, as indicated at 2. This 30 plate is re-enforced by two transverse straps of steel or the like 3 and 4 and two angularly disposed straps 5 and 6 extending between the two first mentioned straps, all these straps being secured to the face of the sheet as by means of rivets 7. Three holes extend 35 through the re-enforcing straps and plate and through these are secured eye bolts 8 to which are secured the lines constituting the bridle, the lines being attached to the mooring line at 40 their other ends.

The bridle consists of lines 9, 10 and 11, extending from the eye bolts 8 to a ring 12 to which their ends are attached by shackles 9a and 10a, the upper cables 9 and 11 being somewhat longer than the lower central cable 10, so that when a pull in a nearly horizontal direction is exerted upon the ring the anchor tends to assume the position shown in Figures 2 and 3 with its upper edge inclined 45 away from the direction of the pull while its

lower edge is inclined toward said direction so that the force tends to cause the anchor to dig downwardly into the earth, and not to remove it therefrom. The greater the pull the more securely does the anchor become imbedded. The leads of the lines of the bridle control to a great extent the manner in which the anchor may be caused to imbed itself. Mooring cable 13 is spliced into ring 12 and extends to the winch or capstan aboard the ship or barge connected to the anchor. By releasing the lower shackle, the anchor may be tripped and readily removed from the earth in which it is imbedded.

Secured to the rear face of the anchor is a 45 downwardly extending pipe 14 terminating at its lower end in a flared narrow nozzle 15. A hose or the like may be secured to the upper threaded end of the pipe and water under pressure forced down through the same to excavate the earth or mud at the bottom edge of the plate, causing the anchor to dig into the earth and securely imbed itself. A trench should be dug for the reception of line 10, the other lines of the bridle remaining 50 above the surface of the ground. In soft ground a plank or the like may be placed under lines 9 and 11 to prevent them from becoming imbedded.

Horns shown as tubular extensions 16 are 55 riveted to the upper corners of the plate 1 extending laterally therefrom so that a sling may be readily attached thereto and the anchor lifted out of the earth when it is desired to shift the same, and by which it may be lowered into a desired position.

From the above it will be seen that I have provided an anchor which presents a broad surface substantially normal to the mooring line and which may be readily caused to imbed itself in a desired position, providing a very secure and positive anchorage, which is easily handled and conveniently stored in small space, due to its flatness and which may be readily and economically manufactured.

While I have described the illustrated embodiment of my invention in some particularity, obviously many modifications and variations thereof will readily occur to those

skilled in the art to which it appertains, and I do not, therefore, limit myself to the precise details shown and described, but claim as my invention all embodiments thereof coming within the scope of the subjoined claims.

I claim:

1. An anchor comprising a substantially flat plate, a bridle secured thereto to cause the same to assume an inclined position relative to a mooring line and to dig into the earth, a mooring line extending from the bridle and hydraulic means for initially causing a portion of the plate to embed itself in the earth.

2. An anchor comprising a substantially flat plate, a bridle having a plurality of cables secured at one end to spaced points in said plate above its center and a shorter cable secured to said plate below its center, said cables being detachably connected at their other ends, a mooring line connected to said bridle at said last mentioned ends, a conduit extending downwardly along one surface of the plate, a wide flat nozzle at the lower end of the conduit secured to the said surface of the plate adjacent its lower edge, and means for supplying water under pressure to said pipe.

3. An anchor comprising a substantially flat plate, re-enforcing members secured to one surface of the plate, a cable secured to said plate above its center, a cable shorter than said first named cable secured to said plate below its center, means for connecting said cables together to form a bridle, a mooring line connected to said bridle at said connecting means, a conduit extending downwardly along one surface of the plate, a wide flat nozzle at the lower end of the conduit secured to the said surface of the plate adjacent its lower edge, and means for supplying water under pressure to said pipe.

4. An anchor comprising a substantially flat plate, attaching means to which a sling may be secured carried by the upper corners of said plate, a cable secured to said plate above its center, a cable shorter than said first named cable secured to said plate below its center, means for connecting said cables together to form a bridle, a mooring line connected to said bridle at said last mentioned ends, a conduit extending downwardly along one surface of the plate, a wide flat nozzle at the lower end of the conduit secured to the said surface of the plate adjacent its lower edge, and means for supplying water under pressure to said pipe.

5. An anchor comprising a substantially flat rectangular plate having curved lower corners, two transversely extending reinforcing bars secured to one surface of the plate, angularly disposed re-enforcing bars between said transversely extending bars secured to said surface of the plate, a bridle comprising

two cables secured at spaced points to the plate adjacent its top and one cable shorter than said first mentioned cables connected centrally to the plate near its bottom, the other ends of said cables being detachably connected together and to a mooring line, a downwardly extending pipe secured to one surface of said plate terminating at its lower end in a flat flared nozzle adjacent the bottom of the plate and secured thereto, and outwardly extending projections secured to the upper corners of said plate.

In testimony whereof I hereunto affix my signature this 24th day of September, 1928.

CHARLES H. CRONEY.
